ELECTROPLATING ANODE

Frederick W. Wagner, Highland Park, Mich., assignor to Wagner Brothers, Inc., Highland Park, Mich., a corporation of Michigan

Application April 5, 1950, Serial No. 154,049

5 Claims. (Cl. 204—288)

1

This invention relates to anodes for use in electrolytic baths and especially to improvements therein whereby more efficient and economical electroplating may be achieved.

It is customary in electroplating procedure to support a soluble or replaceable anode in the electrolytic bath, the electrical circuit through the anode being completed through the anode support which is also submerged at least partially in the bath. As a result, the portions of the anode support in contact with the bath are gradually dissolved, requiring the support to be replaced at considerable expense. If the material of the anode support differs from the soluble anode, the difficulty is compounded since the bath will eventually become contaminated, requiring the replacement of expensive chemicals.

An important object of the present invention is to provide simple improved means for suspending a plurality of vertically spaced soluble anodes in an electrolytic bath, whereby the anode support is completely shielded from the bath and destruction of the support or contamination of the bath are avoided.

Another object is to provide an improved anode for an electrolytic bath comprising a plurality of replaceable soluble apertured anode members strung on an electricity conducting shaft in electrical contact therewith and spaced from each other by a plurality of spacing washers, each including a gasket of material inert to the bath and compressible between the adjacent anode members to provide a fluid tight seat therewith around the shaft. By virtue of this construction, a fluid-tight seal is formed around the body of the shaft to shield the same from the electrolytic bath when the alternating anode members and gaskets are pressed together. Also the anode members may be readily and economically formed in slabs or plates of comparatively large area to contact the bath. The present invention is particularly suitable for use in nickel plating, in which case the anode members will be formed of comparatively pure nickel. It is to be understood however that this invention is not limited to the use in nickel plating processes, since it may readily be applied in the electroplating of other metals.

The aperture or bore through each anode member is preferably dimensioned to fit snugly around the shaft passing therethrough. Nevertheless difficulty in achieving positive electrical contact between the shaft and members is frequently experienced. The resistance of the electroplating circuit is thus increased and inefficient operation results.

2

It is accordingly another object to increase the effective area of electrical contact and thereby decrease the electrical resistance between the shaft and anode members by providing a comparatively rigid electricity conducting inner core or bushing for each compressible gasket, snugly fitting around the shaft in electrical contact therewith and positively abutting in electrical contact the adjacent anode members spaced thereby. This construction increases the effective area of electrical contact between the shaft and anode members by the extent of the area of contact between the shaft and conducting bushings, since the latter complete an electrical unit with said anodes when pressed therebetween in the formation of the aforesaid fluid-tight seals around the shaft.

Another object is to provide an anode assembly of the foregoing nature wherein the axial thickness of each compressible gasket increases radially from a thickness less than the axial thickness of the associated inner bushing adjacent the latter to a thickness greater than said bushing thickness. Accordingly upon compressing the gaskets between the adjacent anode members to effect said seals, electrical contact between the alternate conducting bushings and anode members will not be impaired by reason of the deformed gaskets being forced between adjacent bushing and anode members.

Still another object is to provide an anode assembly of the foregoing character comprising improved means for supporting the shaft in the electrolytic bath and clamping the alternating anode members and spacing washers together to effect said seals around the shaft, comprising an abutment inert to the bath at the lower end of the shaft and adapted to be compressed against a lower spacing washer, so as to effect a fluid-tight seal therewith around the shaft, and also comprising an electricity conducting coupling coated with a material inert to the bath and having uncoated screw threaded portions at opposite ends adapted for screw attachment with the upper end of the shaft and an electricity conducting support for the shaft, the coated coupling being adapted to be tightened against an upper spacing washer so as to effect a fluid-tight seal therewith around the shaft.

By this construction, the replaceable anode members and spacing washers may be readily removed from or strung on the shaft as desired and clamped together to effect a fluid-tight seal completely enclosing the shaft. Also the several electricity conducting parts of the anode assembly are readily separable from each other and re-

placeable in the event that they should inadvertently come in contact with the bath and be dissolved or damaged thereby. In this regard the several conducting parts which might inadvertently come in contact with the bath preferably comprise the same material as the soluble anode members, so that in the event of leakage of one of the seals or of the coating around the coupling, for example, the bath will not be contaminated.

Other objects of this invention will appear in the following description and appended claims, reference being had to the accompanying drawings forming a part of this specification wherein like reference characters designate corresponding parts in the several views.

Fig. 1 is a fragmentary elevation showing parts in vertical mid-section of an anode assembly embodying the present invention.

Fig. 2 is a horizontal section taken in the direction of the arrows along the line 2—2 of Fig. 1.

Fig. 3 is a view similar to Fig. 1, showing the lower portion of the anode assembly prior to clamping the anode members and spacing washers together.

It is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

Referring to the drawings, the anode assembly shown comprises a cylindrical electricity conducting shaft 10 having a plurality of apertured soluble anode members 12 replaceably strung thereon and spaced by a plurality of replaceable washer assemblies each comprising an outer compressible annular gasket 14 and a comparatively rigid annular inner electricity conducting core or bushing 16.

Each anode member 12 comprises in the present instance a generally square slab or plate having a central aperture or bore through which the shaft 10 passes snugly in electrical contact with the sidewalls thereof, Fig. 2. Although the particular dimensions and shape of the members 12 may be varied as desired, the plate or slab constructions shown are particularly feasible and economically obtained.

Each gasket 14 comprises a rubber-like material comparatively inert to the electrolytic bath for which the anode members 12 are intended, so as not to be dissolved or damaged by immersion in the bath. As indicated in Fig. 3, each gasket 14 in the uncompressed condition fits closely but slidably around its associated inner bushing 16 and increases radially outward in axial thickness from a thickness less than the height of the bushing adjacent the latter to somewhat more than the bushing height at the outer periphery of the gasket. Thus when the alternating members 12 and spacing washers 14, 16 are pressed tightly together, Fig. 1, the members 12 will abut the ends of the adjacent inner bushings 16 in positive electrical contact without interference from the adjacent portions of the gaskets 14, which might otherwise be deformed and squeezed between the members 12 and 16, impairing the electrical contact therebetween. However the outer periphery of each gasket 14 which is adjacent the face of one of the members 12 will be deformed and compressed thereagainst in a fluid

tight seal around the shaft 10. In this connection, the central portion of each anode member 12 engaged by the adjacent washer assembly 14, 16 is preferably ground or machined to provide a smooth surface assuring a fluid tight seal with the gasket 14 and a positive electrical contact with the ends of the inner bushing 16. Each bushing 16 is of course preferably similarly finished at its ends and is dimensioned to fit snugly on the shaft 10 in electrical contact therewith, Fig. 2.

Suitable means are provided to enclose the ends of the shaft 10 and clamp the members 12 and spacing washer assemblies 14, 16 together to effect the aforesaid seals, comprising in the present instance a socket or cap nut 18 and a double socket or coupling nut 20 adapted to screw on lower and upper threaded ends 22 and 24 respectively of the shaft 10 and to be compressed against the endmost gaskets 14 to complete fluid-tight seals therewith around said shaft. Inasmuch as the cap nut 18 will usually be formed of metal for the sake of strength, it is coated except at its internally threaded socket with a material 26 inert to the electrolytic bath.

The coupling nut 20 is a conductor of electricity and is provided with a pair of coaxial oppositely opening internally threaded sockets into which are screwed the end 24, as aforesaid, and the threaded end 28 of an electricity conducting supporting rod 30. The latter is adapted to be suspended from a support by means of a hook portion 32 at its upper end, whereby the anode is energized by an electrical current flowing through the rod 30, coupling 20, shaft 10, and from thence to the anode members 12 either directly or through the spacing bushings 16.

Similarly to the coating 26, the coupling 20 is coated except at its two sockets with a material 34 inert to the electrolytic bath. The coatings 26, 34 may comprise the same rubber-like material as the gaskets 14 if desired and preferably do not cover the portions of the nuts 18 and 20 immediately adjacent the endmost bushings 16, since a coating at these locations would only be damaged when clamped against the bushings. Further, the uppermost bushing 16 directly abutting the body of the coupling 20 increases the current flow to the uppermost anode member 12.

It is apparent from the structure disclosed that the soluble anode members 12 and spacing washers 14, 16 may be readily strung as shown on the shaft 10 and compressed together to complete a fluid tight seal around the body of the shaft. The initial compressing may be readily accomplished by placing the shaft 10 with the members 12 and spacing washers 14, 16 assembled thereon in a clamping fixture, whereupon the endmost members 12 are pressed toward each other until the alternating members 12 and bushings 16 solidly abut each other and the gaskets 14 are compressed between the adjacent members 12 to complete the aforesaid seal. Thereafter the nuts 18, 20 are screwed tightly against the endmost washers in a fluid tight seal around the shaft 10, so as to enclose and completely shield the latter and bushings 16 from the electrolytic bath when suspended therein, as for example by means of the supporting shaft 30 screwed into the coupling 20.

In operation, the uppermost anode member 12 will usually be immersed below the level of the bath indicated at 36. The spaced soluble anode members 12 extend radially from the shaft 10 sufficiently to afford adequate area exposed to

the bath for efficient electroplating and gradually dissolve in the course of use. Prior to the danger of leakage around the sealing gaskets 14, the assembly is removed from the bath and the partially dissolved anode members 12 are replaced by new members 12 upon removal of one or both of the nuts 18, 20. The shaft 10, washer assemblies 14, 16 and nuts 18, 20 are used repeatedly.

Also by virtue of the structure disclosed, in the event of inadvertent leakage around one of the sealing gaskets 14 or through one of the coatings 26 or 34 causing damage to some parts of the anode assembly intended to be shielded from the bath, the damaged parts may be replaced without requiring the undamaged parts to be scrapped. In this regard, the conducting parts of the anode assembly, comprising the shaft 10, bushings 16, and nuts 18 and 20 are formed of the same material as the soluble anode members 12 wherever feasible, so as to avoid contamination of the bath in the event of inadvertent leakage.

I claim:

1. In an anode for an electrolytic bath, an electricity conducting shaft adapted to be suspended in the bath while connected with a source of electrical energy, a plurality of anode members and a plurality of washer assemblies replaceably strung on the shaft alternately and spacing each other, each member having a bore with the shaft passing therethrough in electrical contact with the member, each washer assembly comprising a rigid electricity conducting inner bushing in electrical contact with the members spaced thereby and the shaft and also comprising an outer gasket inert to the bath, each gasket having concave faces at opposite sides to provide for maximum compression axially of the gasket adjacent the outer edges of the gasket to effect a fluid-tight seal around the shaft, each gasket interposed between a pair of said members being compressed therebetween with the degree of compression decreasing radially inwardly from a maximum at its outer edge, the uncompressed thickness of the gasket increasing radially from a thickness less than the axial thickness of the associated bushing adjacent the latter to an axial thickness greater than said bushing, and clamping means on the shaft compressing said alternating gaskets and members together to effect said seals and contact between said members and bushings.

2. In an anode assembly for an electrolytic bath, an anode support comprising an electricity conducting shaft adapted to be connected with a source of electrical energy while submerged in the bath, a plurality of apertured anode members replaceably strung on the shaft in electrical contact therewith, a plurality of washer assemblies replaceably strung on the shaft with the members and washer assemblies alternating and spacing each other, each washer assembly comprising an electricity conducting inner bushing fitting on the shaft in electrical contact therewith and with the member on either axial side thereof and also comprising a compressed outer gasket inert to the bath and replaceably fitting around the associated inner bushing, each gasket interposed between a pair of said members being compressed therebetween with the degree of compression decreasing radially inwardly from a maximum at its outer edge, the uncompressed thickness of the gasket increasing radially from a thickness less than the axial thickness of the

associated bushing adjacent the latter to an axial thickness greater than said bushing.

3. In an anode assembly for an electrolytic bath, an anode support comprising an electricity conducting shaft adapted to be connected with a source of electrical energy while submerged in the bath, a plurality of apertured anode members replaceably strung on the shaft in electrical contact therewith, a plurality of washer assemblies replaceably strung on the shaft with the members and washer assemblies alternating and spacing each other, each washer assembly comprising a rigid electricity conducting inner bushing fitting on the shaft in electrical contact therewith and with the member on either axial side thereof and also comprising a compressed outer gasket inert to the bath, each gasket interposed between a pair of said members being compressed therebetween with the degree of compression decreasing radially inwardly from a maximum at its outer edge, the uncompressed thickness of the gasket increasing radially from a thickness less than the axial thickness of the associated bushing adjacent the latter to an axial thickness greater than said bushing.

4. In an anode for an electrolytic bath, an electricity conducting shaft adapted to be suspended in the bath while connected with a source of electrical energy, a plurality of anode members, each having a bore therethrough and being strung on the shaft with the walls of the bore in electrical contact with the shaft, a plurality of washer assemblies strung on the shaft alternately with the anode members in mutually spaced relation, each washer assembly comprising a rigid electricity conducting inner bushing electrically contacting the members adjacent thereto and the shaft and also comprising an outer gasket inert to the bath, each gasket interposed between a pair of said members being compressed therebetween with the degree of compression decreasing radially inwardly from a maximum at its outer edge, the uncompressed thickness of the gasket increasing radially from a thickness less than the axial thickness of the associated bushing adjacent the latter to an axial thickness greater than said bushing, means inert to the bath to hold the members and washer assemblies on the shaft comprising an annular abutment at one end of the shaft, and means to compress said alternating washer assemblies and members together against said abutment to effect said seals.

5. In an anode for an electrolytic bath, a shaft comprising a conductor of electricity adapted to be suspended in the bath while connected with a source of electricity, a plurality of anode members, each having a bore therethrough and being replaceably strung on said shaft with the walls of the bore in electrical contact with the shaft, a plurality of washer assemblies replaceably strung on the shaft alternately with the anode members, each pair of adjacent washer assemblies being spaced by one of said anode members and each washer assembly comprising an electricity conducting inner bushing in electrical contact with the shaft and the anode member on either axial side thereof and also comprising an outer gasket inert to the bath, each gasket interposed between a pair of said members being compressed therebetween with the degree of compression decreasing radially inwardly from a maximum at its outer edge, the uncompressed thickness of the gasket increasing radially from a thickness less than the axial thickness of the associated bushing adjacent the latter to an

axial thickness greater than said bushing, means against which the endmost washer assembly at one end of the shaft is compressed to provide a fluid-tight seal around the shaft comprising an abutment inert to the bath and detachably secured on said end of the shaft, and means for pressing the endmost washer assembly at the other end of the shaft toward said abutment to effect the aforesaid seals between said washer assemblies and members and abutment.
